UNITED STATES PATENT OFFICE.

FRANK X. DELANEY, OF PHILADELPHIA, PENNSYLVANIA.

SHOE-TREE.

1,271,547.

Specification of Letters Patent.

Patented July 9, 1918.

Application filed August 3, 1917. Serial No. 184,198.

To all whom it may concern:

Be it known that I, FRANK X. DELANEY, a citizen of the United States, residing at Philadelphia, in the county of Philadelphia and State of Pennsylvania, have invented 5 certain new and useful Improvements in Shoe-Trees, of which the following is a specification.

My invention consists of an improved 10 shoe tree of the type used to keep shoes in shape while not being worn.

Shoe trees of the above described type which were made prior to my invention usually included toe pieces made entirely of 15 wood or other hard material which would easily slip into a shoe. It is well known that a wooden toe piece is incapable of properly filling the toe portion of the shoe for the obvious reason that after the shoe 20 has been stretched due to wear, the wooden piece which previously fit the toe portion of the shoe is too small to completely fill the toe portion of the stretched shoe.

One object of my invention is to provide 25 a shoe tree which is capable of completely filling the toe portion of the shoe no matter how much the same has been stretched, and will smooth out the wrinkles in the leather.

A further object is to make my invention 30 of a simple and durable construction and so that it can be manufactured and sold at a reasonably low price.

These objects, and other advantageous 35 ends which will be described hereinafter, I attain in the following manner, reference being had to the accompanying drawings in which—

Figure 1 is a sectional elevation of a shoe 40 having my improved shoe tree therein.

Fig. 2 is a transverse section on the line 2—2 of Fig. 1.

Fig. 3 is an enlarged section of a valve which I preferably employ.

Fig. 4 is a transverse section of a pneumatic element which I employ.

Referring to Figs. 1 to 3 inclusive of the drawing, 1 represents a shoe which may be of any type. My invention consists primarily of a head block 2, preferably made 50 of wood in which the end surface 3 is preferably made flat as illustrated in Fig. 1.

A bag or sack 4 is made of rubber and is preferably molded into a shape substan-

tially similar to the inner portion of the toe 5 of the shoe. This bag 4 includes a 55 portion 6 which is cemented or otherwise secured to the surface 3 of the block 2.

An inflating tube 7 leads outwardly from the portion 6 and has a flange 8 which abuts the inner surface of the portion 6. This 60 tube 7 extends into a passage 9 in the block 2, said passage intersecting the surface 10 of said block.

A valve casing 11 is preferably made cylindrical and has screw-threads 12 designed 65 to screw within the end of the passage 9 which is adjacent the surface 10. A valve 13 is located within the casing 11 and a rod 14 extends transversely across the passage and serves as an abutment to limit the 70 inward movement of the valve 13. A cap 15 is adapted to be screwed on the outer end of the casing 11 as clearly illustrated in Fig. 3.

An elongated strip 16 of resilient material, such for example as spring steel, has 75 one of its ends embedded within the block 2, and the other end secured to a knob 17.

In the use of my invention, the bag 4 before it is inflated, can be inserted within 80 the toe portion of the shoe, and the resilient strip 16 can be bowed to permit the knob 17 to engage the inner surface of the heel of the shoe. By removing the cap 15, an air pump such for example as an ordinary 85 bicycle pump, can be screwed on the outer end of the casing 11 and the bag can then be inflated to completely fill the toe portion of the shoe. Sufficient pressure may be attained within the bag 4 not only to properly 90 fill out the toe, but any wrinkles or creases within the toe portion of the shoe will be smoothed out.

The surface 3 of the block 2 forms a backing for the bag 4 while it is being inflated, 95 and since the height of the block 2 is greater than the height of the adjacent portion of the bag 4 before it is inflated, said surface 3 permits a portion of the bag to roll upwardly thereon. This prevents injury to 100 the bag which might otherwise occur if it became congested between the top of the block and the instep portion of the shoe.

In Fig. 4, I have illustrated a form of 105 my invention in which the bottom 18 of the flexible bag 19 is made separately and ce-

mented to the edge portions 20 instead of being made in one piece as illustrated in Fig. 2. In this form of my invention, the bottom 18 can be made of tough material 5 of any suitable nature.

To remove the tree from the shoe, it is merely necessary to manually press the valve 13 inwardly so that the air within the bag 10 can escape and after this has been done the entire device can be easily removed from the shoe.

It will be noted that a device made in accordance with that above described can be used in shoes of various sizes and shapes, 15 since it is merely necessary to pump the bag until the latter completely fills the toe space of the shoe.

While I have described my invention as taking a particular form, it will be understood that the various parts of my invention 20 may be changed without departing from the spirit thereof, and hence I do not limit myself to the precise construction set forth, but consider that I am at liberty to 25 make such changes and alterations as fairly come within the scope of the appended claims.

Having thus described my invention, what

I claim as new and desire to secure by Letters Patent is:

1. A shoe tree including a head block, and a flexible bag having a portion secured to an outer surface of said block, said surface of the block being extended beyond the portion of said bag which is secured thereto 30 to permit a portion of said bag when inflated to roll on the extended portion of said surface, and said block at its top having a smooth curved end surface blending with said extended surface, substantially as described.

2. A shoe tree including a head block, and a flexible bag having a portion secured to an outer surface of said block, said surface of the block being extended beyond the 45 portion of said bag which is secured thereto to permit a portion of said bag when inflated to roll on the extended portion of said surface, substantially as described.

In testimony whereof I have signed my 50 name to this specification in the presence of two subscribing witnesses.

FRANK X. DELANEY.
